US00D601616S

(12) **United States Design Patent**
Mage

(10) **Patent No.:** **US D601,616 S**
(45) **Date of Patent:** **** Oct. 6, 2009**

(54) **SUNGLASS**

(75) Inventor: **Jerome J. M. Mage**, Los Angeles, CA
(US)

(73) Assignee: **Spy Optic, Inc.**, Carlsbad, CA (US)

(**) Term: **14 Years**

(21) Appl. No.: **29/312,011**

(22) Filed: **Sep. 25, 2008**

(51) **LOC (9) Cl. 16-06**

(52) **U.S. Cl. D16/326; D16/329**

(58) **Field of Classification Search** D16/101,

D16/300-342; D29/109-110; D24/110.2;
351/41, 44, 51-52, 62, 158, 92, 103-123,
351/140, 153, 45-46; 2/426-432, 447-449,
2/441, 436-437, 13, 15; D21/483, 659-661

See application file for complete search history.

(57) **CLAIM**

The ornamental design for a sunglass, as shown and described.

DESCRIPTION

FIG. 1 is a front perspective view of the sunglass of the present invention showing my new design;

FIG. 2 is a left side elevational view thereof;

FIG. 3 is a front elevational view thereof;

FIG. 4 is a rear elevational view thereof;

FIG. 5 is a bottom plan view thereof; and,

FIG. 6 is a top plan view thereof.
